UNITED STATES PATENT OFFICE.

CHARLES L. MALONEY, OF DENVER, COLORADO.

DISPLAYING AND VENDING DEVICE.

No. 840,702.

Specification of Letters Patent.

Patented Jan. 8, 1907.

Application filed May 23, 1904. Serial No. 209,400.

To all whom it may concern:

Be it known that I, CHARLES L. MALONEY, a citizen of the United States of America, residing in the city and county of Denver and State of Colorado, have invented certain new and useful Improvements in Displaying and Vending Devices; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in devices for holding and displaying rolls of merchandise, as oil-cloth or any other material put up in rolls and adapted to be sold by unwinding from the roll and cutting it off according to the requirements of the customer.

20 My improved device consists, briefly speaking, of a suitable frame in which is mounted a reel or revoluble device having two heads suitably connected and trunnioned in the frame. Journaled in these heads is a number of roll-holding spindles detachably connected with the heads. The heads are mounted on a central axle provided with a hub having tubes radially disposed in which 25 rods telescope and to whose outer extremities are attached spring-clasps adapted to engage the rolls mounted on the various spindles. Between the hub and each clasp and surrounding the tube and rod are coil-springs normally 30 under tension, having a tendency to force the clasps and rods outwardly. This is to compensate for the reduction in the size of the roll during the unwinding operation, since as the roll unwinds and its size becomes less the 35 spring forces the clasp outwardly for the purpose stated. Any desired number of roll-holding spindles may be employed. One or more of the spindles may have an individual adjustable head, whereby the spindle may be 40 adapted to hold rolls of any length. Provision is also made for measuring and cutting off the material as it is unwound from the roll.

Having briefly outlined my improved construction as well as the function it is intended 45 to perform, I will proceed to describe the same in detail, reference being made to the accompanying drawings, in which is illustrated an embodiment thereof.

In the drawings, Figure 1 is an end elevation of my improved apparatus. Fig. 2 is a section taken on the line 22, Fig. 3. Fig. 3 is a

top plan view of the apparatus. Fig. 4 is a detail view, on a larger scale, illustrating the hub of the device, showing one of the radial tubes and its connections. Fig. 5 is a detail view of the devices connected with the front of the machine for measuring and cutting the goods. Fig. 6 is a section taken on the line 66, Fig. 5, the parts being shown on a larger scale. Fig. 7 is a detail view of a spring-actuated pin for supporting the hinged part of the gage-clamp, the parts being shown on a larger scale than in the other views. Fig. 8 is a top plan view in detail of the device for locking the reel in the desired position, the parts being shown on a larger scale than in the other views.

70 The same reference characters indicate the same parts in all the views.

Let A designate a suitable frame in which is journaled a hollow axle B, whose extremities are journaled in brackets B', mounted on top of the frame and secured thereto by bolts B². To the extremities of this hollow axle or shaft are secured disks C, forming heads which are further connected by rods C', surrounded by spacing-tubes C², interposed between the two heads. On the central part of the hollow axle is mounted a hub B³, having threaded sockets C¹⁵, into which are screwed tubes C⁴, radially disposed and in which telescope rods C⁵, to the outer extremities of which are attached spring-clasps C⁶. Between the clasp and the hub and surrounding the tube and telescoping rod is a coil-spring C⁷. The spring-clasp C⁶ is so constructed that when the roll D is first put in place and of normal size the clasp must be considerably open in order to put the roll in place, whereby the clasp is placed under tension and together with the compensating movement of the telescoping rod clasps the roll until it is completely unwound from the spindle E. Each spindle is journaled in the heads C, and in order to make them readily detachable they engage curved slots C⁸ and when in position are locked in place by hooks C⁹, pivoted on one head, as shown at C¹⁰, and acted on by a spring C¹¹, the spring passing through the end of the pivot C¹⁰, and thereby forming a key to hold the hook in place. It 75 will be understood that there may be any desired number of rotary spindles E, according to the desired capacity of the apparatus. One or more of these spindles E may have an auxiliary head E' adjustable on the spindle by means of a set-screw E², whereby the spindle may be adapted to hold rolls of vary- 80 85 90 95 100 105

ing length. In Fig. 3 of the drawings a short roll D' is shown mounted on the spindle provided with a slidable head E'.

In order to hold the reel in any desired position of rotary adjustment, I employ a locking-pin F, mounted in the guide F', secured to the top of the frame. Between the guide F' and the head of the pin is located a coil-spring F², normally having a tendency to hold the pin in the released position. The pin is provided with a radial projection F³, which enters a slot F⁴, having two parts F⁵ extending at right angles to the body of the slot. When it is desired to lock the reel in position, the pin is moved inwardly through the body of the slot F⁴ and turned sufficiently to bring the projection F³ into one of the angular parts of the slot. The inward movement of the pin causes it to enter a recess G of one of the heads of the reel or drum, and the rotary movement whereby the radial pin F³ is thrown into one of the angular parts of the slot locks the pin in the holding position. When it is desired to release the reel, the action just described is reversed and the projection F³ thrown into the outer angular part of the slot, whereby the pin is locked in the released position. There are a number of these openings G in one head, the number corresponding with the number of rotary spindles and so arranged that when the locking-pin engages one of these recesses the roll mounted on one of the spindles is in position to be unwound therefrom at the front of the machine.

Mounted on the front of the machine is a rigid bar H, to which is hinged at one extremity a bar H', hinges H² being employed. The hinged bar has a slot H³ extending therethrough and registering with a slot H⁴, formed in the bar H, when the hinged bar is in the closed position. At the extremity remote from the hinges H² the hinge and bar is provided with a spring-keeper H⁵, having an offset H⁶, adapted to pass beneath the bar H when the hinged bar is moved downwardly. The keeper is provided with a curved extension H⁷, making its engagement with the bar H automatic when the hinged bar has moved downwardly to the closed position. In order to hold the hinged bar open, the frame is provided with a spring-actuated pin I, mounted in a casing I' and having a shoulder engaged by one extremity of a coil-spring I², the other extremity of the spring engaging the bottom of the casing. This pin is provided with a reduced stem I³, passing through an opening in the bottom of the casing and having a protruding threaded part I⁴, to which is applied a tension-nut I⁵. The acting extremity of the pin is beveled on both sides, and when the hinged bar H' is in the raised position, as shown by dotted lines in Fig. 5, the beveled extremity of the pin will pass beneath it and support it in such position. By virtue, however, of the beveled

end of the pin, the bar H' may be thrown down to the full-line position in Fig. 5 without pulling back the pin, since the latter will automatically recede as sufficient force is applied to the bar H' to throw it to the closed position. 7c

In order to facilitate the holding of the goods between the bars H and H', the hinged bar is provided with a strip H⁸, composed of rubber or other suitable yielding material, located on opposite sides of the slot H³. The hinged bar H' is provided with a central dovetail groove adapted to receive a handle J, carrying a cutter J', which extends downwardly below the dovetail part of the handle 80 or holder and passes through the slot H³ and enters the slot H⁴ when the bar H' is in the closed position. This handle is readily slideable in the dovetail groove of the bar H', whereby the strip of material K may be 85 quickly severed after the desired length of the strip has been drawn from the roll. The casing I' is provided with flanges I⁹, through which are passed fastening devices I¹⁰ for holding the casing in place. 90

To the lower side of the bar H is attached a rod L, upon which is movably mounted a graduated measuring device M. This device is adapted to occupy a vertical position when not in use. When it is desired to use 95 it, it is raised to a horizontal position, whereby the material may be measured as it is drawn from one of the spindles. As soon, however, as the measuring device is released it drops down out of the way. 100

From the foregoing description it is believed that the use and operation of my improved device will be readily understood. Assuming that rolls D and D' are mounted on the device as shown in Figs. 1, 2, and 3, 105 the reel is turned until the roll from which it is desired to remove a portion of the material is brought into the proper position. The pin F is then adjusted, as heretofore described, to engage one of the openings G of the reel, 110 whereby the latter is held in position for the desired length of time. The material is then drawn forwardly over the bar H, it being assumed that the bar H' is raised to the position shown by dotted lines in Fig. 5. By employing the measuring device M the desired length of material is readily ascertained, 115 after which the bar H' is thrown downwardly to the full-line position in Fig. 5 and the cutter J J' employed to sever the piece which 120 has been drawn from the roll. It is evident that as the size of the roll diminishes the spring C² will force the clasp C⁴ outwardly sufficiently to compensate for the reduction 125 in the size of the roll. 130

Having thus described my invention, what I claim is—

1. In a device of the class described, the combination of a reel suitably mounted, a plurality of spindles revolvably mounted on

the reel, the latter having an axle, two telescoping parts one of which is rigidly connected with the axle and to the other of which is applied a spring-clasp, a coil-spring surrounding the telescoping parts and having a tendency to force the spring-clasp outwardly for the purpose set forth.

2. In an apparatus of the class described, the combination of a shaft or axle revolvably mounted, separated heads made fast to the axle, roll-holding spindles journaled in the heads, a number of radial tubes connected with the axle, rods telescoping in the tubes, the outer extremities of the rods being provided with spring-clasps and coil-springs surrounding the telescoping parts and having a tendency to force the clasps outwardly.

3. The combination with a suitable support, of an axle journaled therein, heads mounted on the axle, roll-holding spindles journaled in the heads, the axle having a centrally-located hub provided with radial tubes, rods telescoping in the tubes, springs surrounding the telescoping parts, clasps attached to the outer extremities of the rods and acted on by the springs, and means for locking the shaft in position to allow the material to be drawn from any roll, substantially as described.

30 4. The combination with a suitable support, of a reel provided with an axle revolvably mounted thereon, roll-holding spindles journaled in the reel, radially-disposed tubes connected with the reel-axle, rods telescoping in the tubes and provided with clasps at

their outer extremities, coil-springs surrounding the telescoping parts and acting on the clasps, and a locking-pin mounted on the support and adapted to engage the reel whereby the latter may be held in any desired position of adjustment. 40

5. The combination with a suitable support, of a reel revolvably mounted thereon and provided with a shaft, a plurality of roll-holding spindles journaled in the reel, telescoping parts connected with the shaft, the outer telescoping members carrying clasps acting on the rolls of the spindles. 45

6. In an apparatus of the class described, the combination of a reel provided with an axle, a suitable support in which the axle is journaled, the reel having separated heads fast on the axle, slots formed in the said heads and open on the edges thereof, roll-holding spindles whose extremities engage 50 the said slots, spring-actuated hooks mounted on the heads and engaging the spindle extremities to hold the latter in place, radial telescoping parts connected with the axle, one of said parts having a clasp at its outer 55 extremity, and a spring surrounding the telescoping parts and acting on the clasp to force the latter outwardly, substantially as described.

In testimony whereof I affix my signature 60
in presence of two witnesses.

CHARLES L. MALONEY.
